US00D467961S

(12) **United States Design Patent** (10) Patent No.: **US D467,961 S**
(45) Date of Patent: **** Dec. 31, 2002**

(54) **EYEGLASSES**

(75) Inventor: **Henry Welling Lane**, San Luis Obispo, CA (US)

(73) Assignee: **Dioptics Medical Products, Inc.**, San Luis Obispo, CA (US)

(**) Term: **14 Years**

(21) Appl. No.: **29/156,965**

(22) Filed: **Mar. 8, 2002**

(51) LOC (7) Cl. **16-06**

(52) U.S. Cl. **D16/326**

(58) Field of Search **D16/101, 300-330, D16/335-337, 339-340, 900; D29/109, 110; 351/41, 44, 51, 52, 57-61, 121, 123, 153, 156-158; 2/426, 448, 449, 428, 430, 436, 444**

(56) **References Cited**

(57) **CLAIM**

I claim the ornamental design for eyeglasses, as shown and described.

DESCRIPTION

FIG. 1 is a top perspective view of eyeglasses showing of my new design;
FIG. 2 is a rear elevation view of eyeglasses thereof;
FIG. 3 is a front elevation view of eyeglasses thereof;
FIG. 4 is a top view of eyeglasses thereof;
FIG. 5 is a bottom view of eyeglasses thereof; and,
FIG. 6 is a left side elevation view of eyeglasses thereof, the right side being a mirror image of the left side.

1 Claim, 5 Drawing Sheets
